UNITED STATES PATENT OFFICE.

PHILIP FOUKES, OF PITTSBURGH, PENNSYLVANIA.

SPLICE-JOINT.

1,269,698.

Specification of Letters Patent. Patented June 18, 1918.

Application filed December 7, 1915. Serial No. 65,499.

To all whom it may concern:

Be it known that I, PHILIP FOUKES, a citizen of the United States, residing at Pittsburgh, in the county of Allegheny and State of Pennsylvania, have invented certain new and useful Improvements in Splice-Joints, of which the following is a specification.

My invention relates to the construction of the means employed in securing the girts and diagonal or bracing members to the legs or uprights of derricks, towers, and similar framed structures fabricated from rolled metal shapes.

One object of the invention is to provide a joint of novel construction having improved means whereby the necessity of punching holes in the legs of the derrick to connect the bracing members is avoided and overcome, thereby enabling the cross sectional area and weight per lineal foot of the legs or uprights of the structure to be reduced to a minimum, and the erection of the structure to be facilitated.

A still further object of the invention is the provision of a splice joint for derricks and similar framed structures having the novel combinations and arrangement of parts shown in the accompanying drawings, specifically pointed out in the appended claims and more fully described hereinafter.

Referring now to the drawings, forming part of this specification, Figure 1 is a side elevation showing part of one leg or upright of a derrick, tower, or similar structure having a splice joint constructed and arranged and applied thereto in accordance with my invention.

Fig. 2 is a sectional plan of the apparatus shown in Fig. 1, the section being taken on the line II—II of Fig. 1, showing the girts and diagonals or bracing members secured to the legs of the structure in accordance with my invention.

Fig. 3 is a plan showing a preferred form of bolt used in fastening the bracing members to the angle plates and clamping the angle plates to the legs or uprights in accordance with my invention.

Fig. 4 is a sectional end elevation of the bolt shown in Fig. 3.

Fig. 5 is an inverted plan of the clip forming part of my improved splice joint.

Fig. 6 is a sectional detail taken on the line VI—VI of Fig. 1, showing the pre-

ferred construction of the tongues for locating the angle plates on the derrick legs or uprights.

In the accompanying drawings, the numeral 2 designates one leg or upright of a derrick or tower which as shown is formed of a rolled metal shape known as an angle.

Secured in close holding engagement with the outer surface of two sides of the angle 2 is an angle plate 3 which may be formed by bending a rolled metal plate, as shown, but which also may be formed of a piece of rolled metal angle. The angle plate 3 is clamped and frictionally held in position on the leg 2 by means of clips 4, 4, which are similar in construction, these clips having a rabbet or groove 5 in one edge thereof which is formed to fit and tightly engage with the rounded edges of the sides of the angle forming the leg 2 of the structure. The clips 4 and the angle plate 3 have registering holes therein through which clamping bolts 6 are inserted, these bolts having a square shoulder 7 adjacent to the head 8 thereof, so as to prevent turning of the bolt in the holes in tightening the nuts 9 on the bolts to fasten the parts together.

Also secured to the angle plate by means of the bolts 6 for the clips 4, are the girts 10 and 11, and diagonals 12, 13, and 14, 15, forming the bracing, which are conveniently formed of rolled metal angles in the manner shown. The openings or holes 16 in the ends of the girts and diagonals are rectangular in cross section so as to engage with the sides 90 forming the square shoulder 7 on the head end of the bolts 6, in this way avoiding the necessity of having more than one set of holes in each side of the angle plate 3 in fastening the bracing members and the clips 4 to the angle plate 3 and in clamping the angle plate in position on the derrick leg 2.

In order to quickly position the angle plate on the derrick leg an integral tongue 17 is formed on each leg by slitting the leg as is shown in Figs. 1 and 6, the so-formed tongue being sprung outwardly so as to form a support on which the lower edge of the angle plate 3 rests in determining the position of the angle plate lengthwise of the derrick leg 2.

In assembling the parts to form a derrick with the splice joints made in accordance with my invention, the angles 2 forming the legs of the structure are provided with

the tongues 17 in the shop, but as will be seen by reference to the drawings, no through holes need be punched in the derrick leg to attach the bracing members, so that the strength and stiffness necessary is secured with the use of an angle of much lighter weight than is required when a series of holes are punched in the sides of the angle to fasten the parts together.

10 The bent plate or angle plate 3 is then secured to the leg 2 in the desired position by means of the clips 4 and bolts 6, and when positioning the angle plates 3 on the leg 2, the girts and diagonals are also fastened thereto by the bolts 6.

15 The rectangular holes 16 in the girts and diagonals are elongated so as to provide for adjustment in squaring up the structure. After this is done the nuts 9 on the bolts 20 are turned on the bolts so as to tightly clamp the clips 4 and angle plate 3 on the derrick leg 2 and frictionally hold the angle plate in the desired position. As at the same time the bracing members are fastened to the 25 angle plate, a strong and rigid structure is obtained.

20 The advantages of my invention, which will be appreciated by those skilled in the art, arise from the novel manner of connecting the diagonal members and girts to the legs of the structure, and by the omission of any through holes in the legs of the structure. By avoiding the use of holes in the legs of the structure the cost of fabricating is reduced, while the weight of the 35 structure is materially lessened without sacrifice in strength and stiffness.

30 Modifications in the details of the construction of the splice joint, and the manner of fastening the bracing members thereto, may be made without departing from my invention as defined in the appended claims.

I claim:-

1. A splice joint for derricks and similar structures comprising an angle plate engaging the sides of the derrick leg, said angle plate being adapted to connect the members of the leg bracing, clips engaging the edges of said leg to clamp the angle plate in position thereon, said bracing clips and angle plate having registering holes therein and bolts in said registering holes for securing the clips to the angle plate and thereby

clamping the angle plate on the derrick leg and fastening the bracing to the angle plate. 55

2. A splice joint for derricks and similar structures comprising an angle plate to engage the sides of the derrick leg, clips bolted to the angle plate and engaging the edges of the derrick leg to thereby clamp and frictionally hold the angle plate in position on the derrick leg, said angle plate having the derrick leg bracing fastened thereto, and said bracing, angle plate, and clips having registering holes therein, and bolts extending through said registering holes. 65

3. A splice joint for derricks and similar structures comprising an angle plate to engage the sides of the derrick leg, clips bolted to the angle plate and engaging the edges 70 of the derrick leg to thereby clamp and frictionally hold the angle plate in position on the derrick leg, said angle plate having the derrick leg bracing fastened thereto, and means formed on the derrick leg to engage 75 with and fix the position of the angle plate lengthwise on the leg.

4. In a derrick or similar structure the combination of a leg of the derrick, diagonal braces and girts formed of rolled metal 80 shapes, and a splice joint for fastening the diagonal braces and girts to the derrick leg, said splice joint having an angle plate engaging the sides and clips engaging the edges of said leg, with registering holes in 85 the angle plate and clips, slotted holes in the ends of the diagonal braces and girts, and bolts extending through the slotted holes of the bracing and registering holes in the clips and angle plate, to clamp the 90 parts in assembled relation.

5. In a derrick or similar structure the combination of a derrick leg, girts and diagonal braces, and a splice joint fastening the girts and braces to the derrick leg, said 95 splice joint having an angle plate and clips frictionally engaging the derrick leg, with registering holes in the angle plate and clips, and slotted holes in the ends of the girts and braces, and bolts extending through said 100 holes, to clamp the angle plate on the derrick leg and fasten the girts and braces to the angle plates.

In testimony whereof I have hereunto set my hand.

PHILIP FOUKES.
